UNITED STATES PATENT OFFICE.

JAMES F. MUNSIE, OF BROOKLYN, NEW YORK, ASSIGNOR TO THOMAS LEONARD COLES, OF SAME PLACE.

DUCT FOR ELECTRIC CONDUCTORS.

SPECIFICATION forming part of Letters Patent No. 426,199, dated April 22, 1890.

Application filed October 29, 1889. Serial No. 328,595. (No model.)

To all whom it may concern:

Be it known that I, JAMES F. MUNSIE, a subject of the Queen of Great Britain, residing at Brooklyn, in the county of Kings and State of New York, have invented certain new and useful Improvements in Ducts for Electrical Conductors; and I do hereby declare the following to be a full, clear, and exact description of the invention, such as will enable others skilled in the art to which it appertains to make and use the same.

My invention relates to certain new and useful improvements in ducts for electrical conductors, and more particularly to ducts designed to inclose and protect conductors conveying high-tension currents within the walls and between the partitions of buildings, where danger of fire is to be apprehended should an arc be formed by reason of breaking of the conductor, wearing away of the insulating-coating of neighboring conductors, or similar cause.

The object of my invention is to furnish a duct of the kind referred to, of such construction as to be indestructible by the accidental forming of an arc within it, and protected at its exterior from the depredations of rats and insects, the duct being also readily manufactured from materials of moderate cost.

In the accompanying drawings, Figure 1 represents in longitudinal section one form of an electrical-conductor duct embodying my invention. Fig. 2 represents a cross-section thereof taken on a plane indicated by the line 1 1 of Fig. 1.

Similar numerals of reference indicate similar parts in both figures.

The duct consists, primarily, of an inner tube 3, of capacity suitable to the number of electrical conductors to be conveyed, and a concentric outer tube 4, together with an intermediate filling of powdered refractory material of such character as not to disengage gases when subjected to heat.

The inner tube 3 is made of indurated fiber, or from fire-and-water-resisting paper-stock, preferably made as described in an application for Letters Patent filed by me January 17, 1890, Serial No. 337,246. In said application one of the means described for producing the

stock referred to consists in first treating manila or other paper pulp by washing or boiling the same in a solution of common salt, sulphate of aluminum, and sulphate of zinc, until the entire mass of pulp is completely 55 impregnated with said solution. The solution, after having acted upon the pulp, is then drained off, and an equal part, by weight, of finely-pulverized fire-clay, and an equal part, by weight, of finely-pulverized Portland cement, are added to it, together with a sufficient quantity of white glue and silicate of soda to agglutinate and combine the whole. An intimate homogeneous mixture of these constituent parts is secured by mechanical agitators or mixers. The mixture thus obtained may be molded into pipes, tubes, or ducts under heavy pressure. The molded products are thereupon thoroughly dried in a suitable oven, and while still hot are immersed in a 70 hot bath of india-rubber or of fire-proof paint, (known commercially as "mineral paint.") The hot liquid is absorbed by the heated mass of the article plunged into it, and any existing pores are filled, thereby rendering the article 75 thoroughly water-proof. In order (when rubber is employed) to render said rubber non-inflammable the article may thereafter be subjected to the ordinary vulcanizing process.

The outer tube 4 is preferably of tinned 8c sheet-iron, which, while sufficient to prevent destruction by rats and insects, is inexpensive and readily made.

The intermediate filling 5 is preferably of mica, combined, if need be, with a sufficient 85 percentage of whiting or similar innocuous fire-resisting powder to act as a binding or agglutinating material to the mica, so as to make the latter pack better within the space allotted to it.

The manner of building up or constructing the duct is as follows: The tube 3 is placed within the tube 4, a ring-washer 6, of fire-resisting paper-pulp, being inserted at the tube ends between the two to close the intervening 95 space. Powdered mica or powdered mica and whiting is then poured into the intervening space, and at intervals additional rings, as 7, of fire-resisting paper-pulp are inserted and forced down upon the powdered material to 100

firmly compact it. When the annular space is filled nearly to the opposite end of the duct, additional rings similar to 67 are inserted at said ends to retain the packing and close the annular space.

5 The several rings referred to, besides serving the function of packers, also strengthen the general structure and increase the durability of the duct.

10 Having thus described my invention, what I claim is—

1. An electric-wire duct consisting of concentric tubes having an intermediate filling of powdered fire-resisting material, substantially as described.
2. An electric-wire duct consisting of an inner tube of fire-and-water-resisting material, an outer tube of metal, and an intermediate filling consisting principally of powdered mica, substantially as described.
- 20 3. An electric-wire duct consisting of an inner tube of fire-and-water-resisting material,

an outer tube of metal, an intermediate filling consisting principally of powdered mica, and an agglutinating or binding material, substantially as described.

25 4. An electric-wire duct consisting of concentric tubes having an intermediate filling of powdered fire-resisting material, and packing-rings for said material, substantially as described.

5. An electric-wire duct consisting of an inner tube of fire-and-water-resisting material, an outer tube of tin, an intermediate filling consisting principally of powdered mica, and packing-rings for said filling, substantially as described.

In testimony whereof I affix my signature in presence of two witnesses.

JAMES F. MUNSIE.
